FIG. - 5 -

UNITED STATES PATENT OFFICE.

EUGENE KORN, OF SAN FRANCISCO, CALIFORNIA.

CREASE-RETAINING DEVICE FOR HATS.

1,230,307.

Specification of Letters Patent. Patented June 19, 1917.

Application filed February 24, 1917. Serial No. 150,638.

To all whom it may concern:

Be it known that I, EUGENE KORN, a citizen of the United States, residing at the city and county of San Francisco and State of California, have invented certain new and useful Improvements in Crease-Retaining Devices for Hats, of which the following is a specification.

My invention relates to a device to be applied inside the crown of a hat of the creased or soft-crown type, for the purpose of retaining the crease therein.

The object of the invention is to provide such a device which will be as light as possible and inexpensive to manufacture and easy to apply, but which will have the requisite amount of strength to properly retain the crease in the hat crown; and, moreover, to provide means for retaining the device in position and prevent the same from falling out of place. This latter feature is of very great advantage, for the reason that, as the hat is handled, the crown receives considerable bending and working, and, unless such retaining means is provided, the crease-retaining device is very apt to work loose and drop off. This is particularly true in the case of the so-called cloth hats, in which the crown is very soft and pliable. In such hats, the crease-retaining device must have considerable stiffness, and yet must be sufficiently light to be supported by the relatively soft crown material.

These and other objects will be fully elaborated in the following specification, in which the invention is described in its preferred form, which form is illustrated in the accompanying drawings. It is to be understood, however, that changes may be made in the form and construction of the invention, within the scope of the claim hereto appended, without departing from the spirit of the invention. With this in view, the invention will be fully described with reference to the accompanying drawings, wherein—

Figure 1 is a vertical transverse section through a hat, of the soft cloth type, showing my improved crease-retaining device in position.

Fig. 2 is a side elevation, enlarged, of my crease-retaining device.

Fig. 3 is a transverse section of the same, taken on the line 3—3 of Fig. 2.

Fig. 4 is a plan view showing my device

before being bent to shape to be clamped upon a crease.

Fig. 5 is a side elevation of a modified form of my device.

Referring now more particularly to the drawings, the reference numeral 1 designates the crown of a hat, whose upper portion is inwardly creased, as at 2, in the well known manner. Over this crease on the inside of the hat crown, is fitted my retaining device 3, said retaining device being bent into U-shaped cross section, as shown in Figs. 1 and 3.

The retaining device 3 is cut or stamped from relatively thin sheet metal, preferably aluminum, in the form shown in Fig. 4, having two opposite wings 4 joined by a shorter central portion 5. When placed within the hat, the device is folded longitudinally of this short central portion 5, to bring the wings 4 parallel to each other, as shown in Figs. 2 and 3. One of said wings then lies upon each side of the crease 2 of the hat, as shown in Fig. 1, and the device, being laterally squeezed, securely clamps said crease and retains the same in position.

The outer edges of the device are outwardly flared, as shown at 6, to form a narrow flange. This flange adds stiffness to the device, by resisting bending and buckling strains and also prevents chafing of the cloth or other material of the hat at the edges of the clamp, particularly at the outer folds 2' of the crease, where said cloth or material lies against the long side edges 6' of the clamp.

The wings 4 of the device are provided with inwardly extending projections 7, formed preferably by punching the metal inwardly. These projections press into the cloth or material of the hat-crease 2, as shown in Fig. 1, and prevent the device from slipping or falling off. These projections are of particular advantage when the device is used in soft cloth hats, for the reason that in such hats, being very pliable, the crowns receive considerable bending and distortion, tending to work the clamp loose.

For use in such hats, it may be advisable to provide a plurality of retaining projections 7 in the wings 4 of the clamp, as shown in Fig. 5, although for stiffer hats one such projection in each wing is sufficient.

By making the device with relatively long wings 4, ample support is provided for the upper fold 2' of the crease, at which points

support is most needed; and the relatively short center portion 5 reduces the weight of the device without detracting from its strength, for the bending at this point provides the requisite stiffness. The retaining projections 7, moreover, are preferably positioned slightly below the center, to bring them nearer the bent portion 5, as shown, somewhat exaggerated, in Fig. 1. Said projections are thus placed in the region of greatest stiffness, and are less liable to let go and slip, upon slight spreading of the wings 4, than would be the case if they were nearer the upper edges of said wings.

As will be readily seen from Fig. 4, the device can be completely formed by one stroke of a suitably constructed die, the edges being cut and flanged, and the projections 7 punched, at the same operation.

The device is therefore exceedingly cheap to manufacture, and, being flat, occupies the least possible space in shipment and storage; and finally, being made of aluminum, and provided with the flange 6, said device has the least possible weight consistent with

the requisite amount of strength and rigidity.

I claim:—

A crease-retaining device for hats formed of a single flat piece of metal having relatively long lateral wings joined by a relatively short center portion, said center portion being bent upon itself to cause said wings to lie substantially parallel with each other and to cause the device to assume a U-shaped cross-section adapted to embrace the crease of a hat; a continuous outwardly turned reinforcing flange formed around the entire edge of said device; and inwardly facing substantially conical projections carried by said wings for engaging the material clamped therebetween. 30 35 40

In testimony whereof I have signed my name to this specification in the presence of two subscribing witnesses.

EUGENE KORN.
